UNITED STATES PATENT OFFICE.

WALTER E. HOSCH, OF ST. LOUIS, MISSOURI.

CLOTH MEASURING, CUTTING, AND COST-COMPUTING MACHINE.

1,201,735.

Specification of Letters Patent.

Patented Oct. 17, 1916.

Application filed October 5, 1914. Serial No. 865,066.

To all whom it may concern:

Be it known that I, WALTER E. HOSCH, a citizen of the United States, residing in the city of St. Louis and State of Missouri, have invented new and useful Improvements in Cloth Measuring, Cutting, and Cost-Computing Machines, of which the following is a specification.

This invention relates to certain new and useful improvements in cloth measuring, cutting and cost-computing machines, and has for its general object, to provide a machine of this type which will permit cloth to be measured by simply passing the same through the machine until the required length of cloth has been measured off, without the necessity of setting the machine to measure a definite length of cloth; also to provide a machine which will permit the length and cost of remnants of cloth to be readily ascertained by simply drawing the cloth through the machine, which latter will be operated while the cloth is moving therethrough, and when the end of the cloth passes out of the machine, will cease movement, the indicating and computing devices showing respectively, the length of the remnant down to inches, and the cost thereof, to the nearest quarter, or other fractional part of a yard; also to provide a machine of this character which will be operated by drawing the cloth through the same to indicate the length and cost of any given length of material, and the movement of which machine may be reversed by simply drawing the cloth through the machine in the opposite direction to that in which it was first drawn through the machine, in the event the clerk should inadvertently measure off a greater length of material than was requested, or the customer should decide upon a less amount of the cloth than that first measured off; and which, as soon as the movement of the cloth therethrough in either direction is stopped, will indicate the length of material passed through the machine, and the cost thereof; also to provide a machine of this type which shall be simple and compact in construction, and reliable in operation, and one which may be economically manufactured.

With the above general objects in view, the invention comprises, essentially, an indicating device, having a dial with two circular series of figures arranged thereon, and two hands adapted to move over the dial

in the manner of the hands of a clock; one hand being designed to designate the figures of one series, which indicate yards, and the second hand to designate the figures in the other series, which indicate inches; means for turning said hands operated by the movement of cloth drawn through the machine; means permitting the ready re-setting of the hands to the zero position, after each measuring operation; a cost indicating drum, and means for operating the same simultaneously and in synchronism with the movement of the hands over the dial.

Combined with the above features of the machine, is a cutting device which, while not in itself being a novel idea, embodies certain novel features of construction which constitute subsidiary but important features of the present invention.

In the accompanying drawing, Figure 1, is a plan view of the machine with a portion of the top thereof broken away to illustrate a portion of one of the friction rolls; Fig. 2 is a view in end elevation, a portion of the top of the casing being broken away to indicate certain parts of the driving mechanism; Fig. 3 is a side view, partly in section and partly in elevation; Fig. 4 is a fragmentary section on the line 4—4 of Fig. 3; Fig. 5 is a similar view on the line 5—5 of Fig. 3; and Fig. 6, is a detail fragmentary view of a portion of the computing drum.

Referring now to the drawings, the numeral 1 indicates a casing in which is housed the cost-computing drum and the gearing for operating the same; and the numeral 2 indicates a housing supported on and secured to the top of casing 1, and in which is housed the gearing or driving mechanism which secures the movement of the hands over the indicating dial, and the rotation of the cost-computing drum, by the passing of the material to be measured through the machine.

The casing 2 has an integral, laterally-projecting portion 3. Mounted on the top of casing 1, and extending parallel with, but at a distance from the projecting portion 3, is a supplementary housing 4, the construction providing a space 5 between the parts 3 and 4, as clearly shown in Fig. 2. Located in the housing 4 is a driving roller 6, preferably of rubber, which projects upward through a longitudinal opening 7, in the top of housing 4. The driving

roller 6 is fast on a shaft 8, which has a bearing at one end in the upper part of a standard 9, located within the housing 4, and at its other end in a standard 10, located in the housing 2, near one side thereof. The shaft 8 is provided beyond the housing 4 with a worm 11, which is in mesh with a worm-gear 12, mounted as later described. The shaft 8 has secured on its outer end beyond the standard 10, a gear 13, which is in mesh with a spur gear 14, mounted on a stub shaft 15, the latter being supported by having its inner end threaded and screwed into a boss 16, provided on the upper end of a standard 17, Figs. 2 and 5. Formed integral with, or secured to, the spur gear 14, and located on the inner side thereof, is a relatively small beveled gear 18, which is in mesh with a larger beveled gear 19, which is fastened on or formed integral with a sleeve 20. Secured on the upper end of the sleeve 20 is a knob 21, having its outer surface knurled as shown by Fig. 4, and projecting outward from this knob is a hand or indicator 22.

The worm gear 12 is fastened on the lower end of the sleeve 23, and on the upper end of said sleeve is secured a ratchet member 24. The worm gear 12 is supported on a bearing 25, which is secured in an opening in the top 26 of casing 1. The bearing 25 and the worm gear 12 are centrally apertured, which apertures are in alinement and of the same diameter as the bore of the sleeve 23, and extending upward through said bearing, worm gear, and sleeve, is a vertical shaft 27, which has secured to its upper end, a knob 28, having its outer surface knurled, as shown by Fig. 2; the knob 28 is provided with a hand or indicator 29, which is somewhat shorter than the indicator 22, the latter corresponding to the minute hand of a clock, and the indicator 29 to the hour hand.

46 The numeral 30 indicates a pin which extends transversely through the upper end portion of the shaft 27, and projects outwardly from either side thereof, said projecting ends normally resting in spaces between teeth of the ratchet member 24. The knob 28 is provided on its under side with a recess 31, which incloses the ratchet member 24 and pin 30, so that these parts are concealed from view.

50 Secured on the lower end of the shaft 27 is a flanged gear 32, the flange of which is provided with equally-spaced notches 33, which are adapted to engage equally-spaced studs 34, secured to the inner face of a disk 35, which is mounted to revolve on a stub-shaft 36, which is in turn riveted in a bracket plate 37 secured at its upper end to the top 26 of the casing 1. The notches 33 are of sufficient depth to permit the shaft 27 to be raised a sufficient distance to lift pin 30 out

of engagement with the ratchet member 24, without effecting disengagement of said notches, or any of them, with the studs 34.

The bracket plate 37 projects forwardly beyond the disk 35, as shown by the dotted lines in Fig. 3, and a similar bracket plate is provided on the opposite side of the machine, and in the outer ends of these bracket plates are secured studs 38, which project inwardly and afford bearings for the recessed ends of a shaft 39. Collars 40 are secured on the shaft 39, near opposite ends thereof, and on these collars are mounted disks 41, extending between and around which, and suitably secured to said disks, is a shell, preferably of paper. The said disk and shell constituting a cylinder 42. Around the periphery of this cylinder, and extending parallel with the axis thereof, are arranged columns 43 of numbers Fig. 6; the numbers indicating the cost of given lengths of material at different prices per yard, and each column having at its head numbers or fractional numbers, as indicated by the numeral 44, indicating the length of material to which the prices in the corresponding column 43 apply. Immediately above cylinder 42, the top of the casing 1 is provided with a longitudinal opening 45, extending throughout the length of said cylinder, the portion of the casing containing the slot 45 being shaped to hold in position a lens 46, which is of the same length as the slot 45. This construction permits the operator to see the numbers on the shell 42, the lens of course, magnifying the size of the numbers to make them more readily visible. Secured on one of the disks 41, at a slight distance therefrom, is a gear 47, the recesses between the teeth of which are adapted to engage over the studs 34 on the disk 35, so that the cylinder 42 will be revolved by and in unison with the disk 35.

Extending along the one edge of the slot 45 is a strip 48, having arranged thereon a series of numbers, indicating the price per yard, said prices running from two cents up to three dollars, as indicated in Fig. 1, and said numbers being arranged to be directly opposite the numbers in the various columns 43, so that as the cylinder 42 is turned, in the operation of the device, to a given position, according to the length of material purchased or measured, the number at the head of the column 43 will indicate the length of material measured; and by running the eye down the column 48 until the number is reached indicating the price per yard at which the material was sold, the number on the cylinder 42 directly opposite such price number will indicate the cost of the length of the material measured.

The numeral 49 indicates a dial mounted on the top of housing 2, which dial is provided with an outer circular series of num-

bers 50, with which the hand 22 coöperates at an indicator, and an inner circular series of numbers 51, with which the hand 29 coöperates as an indicator.

5 The numeral 52, Fig. 3, indicates a lever which is pivotally mounted at 53 in bearings provided on a standard 54, which in turn is mounted on the top 26 of the casing. One end of the lever 52 projects through an 10 opening 55 provided in the side of housing 2, and has mounted thereon a knob 56. The opposite end of the lever 52 is provided with a hook 57, with which engages one end of a coil spring 58, the other end being engaged 15 in a hook 59, mounted on the top 26 of the casing. Projecting laterally from lever 52 near the last described outer end, is an integral frame 60, Fig. 1, in the outer end of which is pivotally mounted one end of a shaft 61, 20 on which is secured a pressure roller 62, the other end of said shaft being rotatably mounted in the lever 52 as indicated in Fig. 3. The roller 62 is likewise preferably of rubber, and is designed to coöperate with 25 the driving roller 6, to maintain material placed between the rollers in frictional contact with the roller 6, so that the latter will be turned by drawing the material between the rollers.

30 The standard 54 has secured thereon a laterally projecting member 63 Fig. 4, the upper edge of which is sharpened to provide one member of a cutter or shear. Pivotally mounted at 64 on the side of said standard 54, is the second member of said shear, indicated by the numeral 65, the member 65 having its lower edge sharpened to coöperate with the upper edge of the cutter 63. The cutters 63 and 65 project through an 35 opening 66, in the side of the housing 2. The lever 52 has a lateral, integral projection 67, which also extends through the opening 66 in the side of the housing, and said projection 67 carries a stud 68, which works in a 40 slot 69 provided in the cutter 65. The rear end of the cutter 65 is provided with a shoulder 70. Pivotally mounted at 71 on the standard 54, is a dog 72, the upper end of which is normally pressed into contact with 45 the rear end of the cutter 65 by a spring 73 secured on the top 26, as indicated at 74.

The numeral 75 indicates one arm of a bell crank lever, which is pivoted at 76 in the wall of the housing 2; the other member 77 of 50 said lever, projecting through an opening in the end wall of said housing, and affording a thumb-piece. The lower end of the member 75 of the bell crank lever engages the lower end of dog 72, so that by pressing down on 55 the thumb-piece 77, the upper end of said dog will be moved out of engagement with the shoulder 70, thereby permitting the spring 58 to draw down the inner end of the lever 52, which motion, through the engagement 60 of the stud 68 in the slot of the cutter 65, raises said cutter, such position of the parts being shown in Fig. 4.

The cutters are arranged in line with the rollers 6 and 62, and are used as a starting point for measuring the material; that is to say, in the measuring operation, the end of the material is carried to the cutters and then, after the required length of material has been drawn between the rollers, the edge portion of the material is placed between the cutters, and the cutter 65 is operated to slit the edge of the cloth.

The operation of the device is as follows: It being desired to measure a certain length of goods, the operator inserts the end portion of the material between the rollers and places the end of the material opposite the cutters. The thumb-piece 77 is then pressed down, which permits the spring 58 to draw the roller 62 down upon the material and press it firmly into contact with the roller 6. The material is then pulled between the rollers, and the movement of the goods will rotate the roller 6, which will in turn, through the worm 11 and the worm gear 12, operate the sleeve 23 and knob 28, with its hand 29; and through the medium of the gears 13, 14, 18 and 19, the sleeve 20, with its knob 21 and hand 22. As the sleeve 23 revolves, the ratchet member 24, engaging the pin 30, will cause the shaft 27 to revolve, thereby through the medium of the flanged gear 32, studded disk 35 and gear 47, causing the cylinder 42 to be revolved. The gearing operating the hand 22 is proportioned to cause said hand to rotate twelve times faster than the hand 29, which is operated by the worm gear 12, and one eighth as fast as the surface speed of the roller 6, which is $4\frac{1}{2}$ " or $\frac{1}{8}$ of a yard, in circumference. The outer series of numbers on the dial 49 are arranged to divide the dial into thirty-six equal parts, representing inches, and the series of numbers 52 are arranged to divide the circular space enclosing them into twelve equal parts, which indicate yards. Thus, when the hand 22 has been caused, by the rotation of the roller 6, and the gear mechanism described, to rotate once around the dial, thus measuring thirty-six inches, the hand 29 will have moved, through the worm gear mechanism, to a position opposite the digit "1" on the inner series of numbers. Assuming that the purchaser desires eleven and one-half (11 $\frac{1}{2}$) yards of material, the movement of the cloth between the rollers is continued until the hand 29 passes the numeral "11" of the inner series of numbers, and the hand 22 lies opposite the numeral "18" of the outer series of numbers, when further movement of the material will be stopped, the edge of the goods inserted between cutters 63 and 65, which will then be in the position shown in Fig. 4, and knob 56 pressed downward, causing the

edge portion of the material to be cut at the correct point, and at the same time lifting the roller 62 out of contact with the material, to permit the material to be removed from between the rollers. The operator then cuts off the material with a pair of scissors, or tears off the length, at the cut, if the goods are of a kind permitting this latter to be done. Assuming the price of the material purchased was six (6) cents a yard, the operator would then look for the cost price in the column 43, headed by "11 $\frac{1}{2}$ " lying opposite the digit "6" in the column 48, which would at once show the cost of the material measured was sixty-nine (69) cents. The cost of any amount of material, from one-fourth ($\frac{1}{4}$) of a yard up to eleven and three-fourths (11 $\frac{3}{4}$) yards, would be similarly ascertained.

It will at once be apparent that there is a close resemblance between the dial 49 and the hands operating over the same, and a clock dial with its minute and hour hands. Thus the position of the hands 22 and 29, indicating eleven and one-half (11 $\frac{1}{2}$) yards, would be the same as the position of the hands of a clock indicating half past eleven (11:30), and the position of the hands of the dial indicating eleven and one-fourth (11 $\frac{1}{4}$) yards, would correspond to the position of the hands of a clock indicating a quarter past eleven (11:15); and so on with other numbers. The operator need scarcely more than glance at the dial to readily ascertain when the desired amount of material has been measured off. When the machine is used for measuring remnants of an unknown length, the same operation is followed, except that the hand 22 is first advanced three (3) inches and the whole length of material is drawn between the rollers, and as the end of the material passes from between the rollers, the latter will, of course, cease to be rotated, and the hands 22 and 29 stop movement. Their position will then indicate the total length of goods passed between the rollers, the smaller hand 29 indicating, as above described, the number of yards measured, and the larger hand 22, the number of inches of material in excess of the given number of yards measured. As the shears are three (3) inches from the rollers, in measuring remnants the hand 22 is first advanced three (3) inches, as stated, to allow for this distance, as the length of goods projecting from the rollers to the shears does not pass over the driving roller and therefore would not be registered if this allowance were not made.

In either use of the device, that is to say, for measuring off a desired quantity of material, or for ascertaining the length of a given piece of material, the hand 29 can be referred to as indicating yards, and the hand 22 as indicating inches, and fractions of a

yard, and in order to facilitate the use of the hand 22 for indicating fractions of yards, I preferably divide a circle containing the one inch division marks for the outer series of numbers, into eight parts, by prominent division marks, as shown in Fig. 1, to indicate $\frac{1}{8}$, $\frac{1}{4}$, $\frac{3}{8}$, $\frac{1}{2}$, $\frac{5}{8}$, $\frac{7}{8}$, and $\frac{3}{4}$ yards.

As heretofore alluded to, my machine permits ready alteration of the length of goods measured in cases where the customer changes his or her mind, and orders a less amount of material. In such case, all the operator has to do is to simply draw the material in the reverse direction from that in which it was moved in the initial measuring operation, until the hands indicate the length specified by the customer.

It will be seen from the above, that my machine can measure any required length of material, that no setting of the machine is required in measuring, and that it will indicate the length of a piece of goods drawn entirely through the machine. This latter function is extremely valuable in measuring up remnants when taking stock.

After the machine has been used in the measuring operation, the hands 22 and 29 must be returned to the zero position indicated in Fig. 1. To accomplish this, the operator grasps the knob 28 and lifts the same to raise the pin 30 out of engagement with the ratchet 34, and then by turning the knob the hand 29 may be readily brought to the zero position. At the same time that this is done, the cylinder 42 will likewise be turned to the zero position, as the depth of the notches 33 permits the flanged disk 32 to be raised a sufficient distance by the shaft 27 to enable the pin 30 to be moved out of contact with the teeth of the ratchet, without removing said notches out of engagement with the studs 34. At the same time that the knob 28 is thus turned, the hand 22 may be brought back to zero position by simply turning the knob 21, the connected gearing, in this case, permitting of such movement; whereas, in turning the hand 29, the pins 30 must be raised out of engagement with the sleeve 23, as stated, for the reason that the worm gear 12 cannot be rotated by the sleeve, as the former is in mesh with the worm 11.

I claim:

1. A cloth measuring machine having a scale thereon comprising a circular series of numbers indicating yards and a separate circular series of numbers indicating inches, a pair of indicators, one of which co-operates with the numbers indicating yards and the other with the numbers indicating inches, upright members supporting the respective indicators and one of which members is inclosed within the other, a cost-computing drum, a price scale co-operating therewith, mechanism operatively connecting said cost-com-

puting drum with one of said members whereby the cost-computing drum will move in synchronism with the indicator supported by said member, a driving roll, mechanism 5 adapted to be operated by drawing material over said roll to rotate said members and thereby move said indicators at different rates of speed, but in defined relation to the length of material drawn through the machine, and to simultaneously rotate the cost-computing drum whereby, on cessation of movement of the material the said indicators will be brought to rest and their position will designate the length of material 10 drawn through the machine in yards and fractional parts of a yard, respectively, and the appropriate figure on the cost-computing drum opposite the figure on the price scale indicating the price per yard of the material will show the cost of the length of material measured, and means for disconnecting at will the member connected with said cost-computing drum with its indicator from said mechanism without breaking the connection with the cost-computing drum, whereby to permit such indicator and the cost-computing drum to simultaneously return to the zero position.

2. A cloth measuring machine having a scale thereon comprising a series of numbers indicating yards, and a separate series of numbers indicating inches, a pair of indicators coöperating with the respective series of numbers, means adapted to be operated by drawing the material to be measured through the machine to move said indicators at different rates of speed and in defined relation to the movement of the material through the machine, said means comprising a rotatable sleeve, a circular ratchet member mounted on the end thereof, a movable support carrying one of said indicators and a pin adapted to engage said ratchet member, the construction permitting said pin to be moved free of the ratchet member to enable the indicator carried by said support to be turned to the zero position.

3. A cloth measuring and cost-computing machine having a scale thereon comprising a series of numbers indicating yards, and a separate series of numbers indicating inches, a pair of indicators coöperating, respectively, with the two series of numbers,

means adapted to be operated by drawing the material to be measured through the machine, to move said indicators at different rates of speed, and in defined relation to the movement of material drawn through the machine, whereby, when the movement of the material ceases the position of said indicators will indicate the length of material drawn through the machine in yards and inches, respectively, a cost-computing drum, an actuating member connected therewith, a driving member co-acting with said actuating member, and bodily movable for a given distance without breaking its connection with said actuating member, said means comprising a rotatable sleeve having a circular ratchet member mounted on one end thereof, and a shaft secured at one end to said driving member and carrying at its opposite end one of said indicators and a pin adapted to rest between the teeth of said ratchet member, the construction permitting said shaft to be raised to lift the pin out of engagement with said ratchet, and to be rotated independently of said ratchet, to return said indicator and the cost-computing drum to the zero position.

4. In a machine of the class described in combination with a driving roll over which the material to be measured is adapted to be drawn, a pivoted lever, a pressure roll carried thereby, a spring connected to said lever and adapted normally to draw said pressure roll against the driving roll, a fixed cutter mounted on the machine, a pivotally mounted cutter coöperating therewith and having a slot, a stud on said lever working in said slot, a pivoted dog adapted to engage said movable cutter to hold the same in a closed position and the pressure roll in an elevated position, when said parts have been thus moved by said lever, and means for throwing said dog out of contact with said cutter to permit the spring to simultaneously depress the pressure roll and raise said movable cutter.

In testimony, whereof, I have hereunto set my hand in presence of two subscribing witnesses.

WALTER E. HOSCH.
